UNITED STATES PATENT OFFICE.

JOSEPH E. FAZAKERLEY, OF PITTSFIELD, MASSACHUSETTS.

HOSPITAL-BED.

1,203,721.

Specification of Letters Patent. Patented Nov. 7, 1916.

Application filed June 1, 1915. Serial No. 31,395.

To all whom it may concern:

Be it known that I, JOSEPH E. FAZAKERLEY, a citizen of the United States, residing at Pittsfield, in the county of Berkshire and State of Massachusetts, have invented certain new and useful Improvements in Hospital-Beds, of which the following is a specification.

My present invention relates to beds designed more particularly for the use of hospital patients, invalids and others who are ordinarily obliged while confined to their beds to resort to the use of pans or hand vessels for the reception of fecal and urinary discharges, including rectal and urethral injections and douches.

The invention comprises improved means for facilitating and receiving discharges of the character referred to, in combination with a bed of the class described.

One object of the invention is to enable the occupant of the bed to make the necessary discharge without requiring the presence and aid of an attendant immediately before, during or after the discharge.

A further object is to enable the patient to make the discharge without shifting the position of the body or adjusting the same to the receiving vessel in the manner heretofore usual.

A still further object is the provision of mechanical means for accurately adjusting and withdrawing the receiving vessel before and after use.

With the foregoing and other objects in view, the invention consists in the construction, combination, arrangement and operation of parts as hereinafter described, and claimed, reference being had to the drawings forming a part of this specification, wherein I have shown a specific useful form of embodiment of the invention and wherein,

Figure 1 is a top plan view of a bed constructed in accordance with the preferred form of the invention and showing the operable parts in closed or normal position, the usual sheets and blankets for covering the body of the patient being temporarily removed; Fig. 2, a view similar to Fig. 1 and showing the relative positions of the operable parts after elevating the receiving or discharge vessel into position for use; Fig. 3, a vertical sectional view on the line A—A of Fig. 1, looking toward the foot of the bed; Fig. 4, a similar view on the line B—B

of Fig. 2, showing the relative position of the operable mechanism after elevating the receiving vessel into position for use; Figs. 5 and 6, bottom plan views of the parts shown in Figs. 3 and 4 respectively; Fig. 7, a detail bottom view of one of the carriages for the support of the intermediate mattress sections; Fig. 8, a detail top plan view of the bed with the mattress removed, the ends of the bed frame, and portions of the mattress carriages and cross-bars supporting the same being partly cut away to disclose the relative positions of the parts thereunder; and Fig. 9, a detail end view of one of the covers for the discharge vessel.

The bed frame may be of any suitable size or formation and constructed of any suitable material, but it is herein shown to be of the usual rectangular formation comprising side-bars or rails 1, 1, head and foot pieces or end-bars 2, 2, preferably formed of channel iron, and two parallel spaced cross-bars, 3, 3, extending between the side-bars centrally thereof and preferably formed of T-beams, the said several parts being securely but not necessarily permanently connected together. The spaces thus formed within the bed frame at opposite ends of the bed are spanned by separate stretchers 4, 4, of any suitable construction, but preferably formed of wire or fabric woven or netted to provide a yielding mattress-supporting medium of open structure.

Mounted to move on the cross-bars 3, 3, are shown separate mattress carriages 5, 5, arranged thereon end to end and provided on their lower faces with roller casters 6, 6, suitably distributed to permit the carriages 5, 5, to be moved toward and away from each other laterally of the bed frame. The carriages 5, 5, are herein shown to be of open structure comprising side and end bars 7, 7, 8, 8, preferably integrally connected in rectangular formation, the end-bars 8, 8, being connected centrally also by an intermediate longitudinal bar 9. The spaces thus formed in the carriage structure on opposite sides of the bar 9 may also be spanned with stretchers 4', 4', as shown, similar to the stretchers 4, 4, above described. Lateral displacement of the carriages 5, 5, when being shifted in position upon the cross-bars 3, 3, as hereinafter described, is prevented by horizontally arranged guide-wheels 10, 10, etc., pivoted to the side bars 7, 7, and projected beyond the outer edges thereof for

engagement with longitudinal up-turned flanges 11, 11, provided on the upper face of the cross-bars 3, 3.

Mounted on the carriages 5, 5, and stretchers, 4, 4, 4', 4', are separate mattress sections 12, 12, 13, 13, of corresponding sizes, which collectively and in normal relation form a continuous mattress arranged in a common plane.

Disposed under the adjacent ends of the mattress sections 13, 13, and below the carriages 5, 5, is shown a portable discharge vessel 14, which is supported upon a plate or elevator 15 having upturned flanges 16, 16, on its front and rear edges, said plate being suspended from the mattress carriages by means of hangers 17, 17, pivoted at their lower ends to said flanges and at their upper ends to suitable brackets 18, 18, provided centrally on the side-bars 7, 7, of the carriages.

The end-wise displacement of the mattress carriages 5, 5, and the simultaneous elevation of the discharge vessel 14 into position for use by the patient is accomplished by means of handles or levers 19, 19, provided preferably on each side of the bed within the patient's grasp and attached to opposite ends of a transversely arranged control shaft 20 journaled at opposite ends in depending apertured supports 21, 21, fixed to the inner side of the side-bars 1, 1, the rotation of the shaft being regulated preferably by means of adjustable spring clamps 22, 22, secured to the underside of the side-bars 1, 1, and provided with adjusting thumbscrews 23, 23, etc., for regulating the tension exerted by the clamps upon the shaft 20. Said shaft 20 carries centrally a fixed pinion 24 adapted to mesh with a rack 25 mounted to move lengthwise in a channel-block 26 carried on the underside of a plate 27 secured to the forward cross-bar 3 and projecting forward under the forward stretcher 4, said plate 27 being herein shown as laterally provided with dependent apertured shoulders 28, 28, for the reception of the shaft 20. As shown, the forward end of the rack 25 is provided with a U-head 29, which is connected at opposite ends to the middle of the central or longitudinal bar 9 of the mattress carriages 5, 5, on each side of the bed by means of pivotally secured thrust-bars 30, 30.

As shown, automatic adjustable covers 31, 31 are provided to cover the vessel 14 when not in use to prevent the escape of any offensive odors therefrom. Said covers 31, 31, are constructed of metal plates normally positioned over and extending across the top of the vessel 14, the inner edges of the covers being arranged to engage each other centrally of the vessel, and are slidably mounted at opposite ends to lateral arms 32, 32, etc., provided at a predetermined angle on

the inner edge of the hangers 17, 17, etc., said arms 32, 32, being connected together by rods or bolts 33, 33, etc., provided at opposite ends thereof and projecting through upturned slotted flanges 34, 34, etc., provided at opposite ends of the covers 31, 31, and extending from points near the inner margin of the covers across the same and projecting beyond the outer margin thereof. In alinement with the lateral arms 32, 32, and on the opposite sides of the hangers 17, 17, are shown additional lateral arms or extensions 35, 35, etc., which are slotted to receive bolts 36, 36, for projection therethrough, the outer ends of the bolts being arranged to support the slotted ends of the pull-bars 37, 37, pivoted at their lower ends to depending lugs 38, 38, etc., provided at the corners of the plate 15, said bolts 36, 36, being projected through suitable closed transverse apertures 39 provided at the outward extremities of the flanges 34, 34, of the covers 31, 31, and beyond the slots therein and operating to push said covers inward, restoring them to normal position over the vessel 14 when the action of the shaft 20 is reversed by the operator.

The vertical movements of the vessel 14 and the elevator or plate 15 upon which it rests are guided by means of two vertically arranged fixed tongues 40, 40, secured at their upper ends centrally to the cross-bars 3, 3, of the bed frame, said tongues 40, 40, being arranged to operate between parallel shoulders 41, 41, etc., formed on the outer side of the flanges 16 of the plate 15.

The discharge vessel 14 is preferably provided with a grip or handle 42, by which it may be removed after use. A lip or stop 43 is shown on one side of the plate 15 to properly align the vessel when being replaced thereon after use. A flag or indicator 44 is also shown on opposite sides of the bed to indicate to an attendant that the discharge vessel should be removed. Said flag is provided with a stem 45 which projects through a suitable transverse opening provided in the side-bars 1, 1, of the bed frame and arranged to be moved outward by engagement with a depending stop 46 provided on the lower faces of the mattress carriages 5, 5, when the latter are thrust apart in elevating the vessel 14 for use.

In operation, the handle 19 is grasped by the operator and raised from a horizontal to an upright position. The consequent rotation of the shaft 20 and pinion 24 moves the rack 25 rearward and therewith the thrust-bars 30, 30, forcing the carriages 5, 5, and mattress sections 13, 13, apart and exposing the discharge vessel 14, which is synchronously elevated on the plate 15 through the medium of the hangers 17, 17. As the plate 15 rises and the hangers 17, 17, are spread apart, the covers 31, 31, are withdrawn from position

over the vessel 14 and are free to drop downward on the lateral arms 32, 32, by gravity. Owing to the tension exerted on the shaft 20 by the clamps 22, 22, etc., the vessel 14 will 5 remain at any given elevation and consequently rest at its upper limit of movement until the action of the handle 19 is reversed, at which time the reverse of the action of the parts operated as previously described 10 thereupon occurs. As above stated, during the reverse movement of the handle 19, the covers 31, 31, are forced back into normal position over the vessel 14 by the inward movement of the bolts 36, 36, connecting the 15 outer ends of the pull-bars 37, 37. The flags or indicators 44, 44, may be readjusted by hand when necessary by an attendant.

It may be observed that the mattress sections 12, 12, 13, 13, are intended to be provided with separate slips or covers, as the use of a single sheet under the patient covering the entire area of the mattress would cover the opening provided between the mattress sections 13, 13, when moved apart 25 as hereinbefore described.

I claim:—

1. In a bed of the character described, the combination with a bed frame of open structure, a mattress support carried on the 30 frame and having a closable transverse opening therethrough, a mattress carried on the mattress support and having a closable transverse opening over said opening in the mattress support, and a receptacle detachably secured to the frame and disposed normally below the location of said openings in the mattress and mattress support, of means for opening the mattress and mattress support to receive said receptacle, said means 35 operating to synchronously elevate the receptacle into position for use.

2. In a bed of the character described, the combination with a bed frame of open structure, a mattress support carried on the 45 frame and having a closable transverse opening therethrough, a mattress carried on the mattress support and having a closable transverse opening over said opening in the mattress support, and a receptacle detachably secured to the frame and disposed normally below the location of said openings in the mattress and mattress support, of means for opening the mattress and mattress support to receive said receptacle, and 50 for synchronously elevating the receptacle 55 into position for use, said means being operable to close said openings in the mattress and mattress support and to synchronously restore said receptacle to its original position.

3. In a bed of the character described,

the combination with a bed frame of open structure, a mattress support carried on the frame and including relatively adjustable members arranged centrally thereof for providing a closable opening through the mattress support, a mattress carried on the mattress support and comprising a plurality of independent sections, a portion of which sections are movable with said adjustable 65 members of the mattress support, and an adjustable receptacle disposed under the frame adjacent the closable opening in the mattress support, of means operable by the occupant of the bed for simultaneously 70 spacing the said adjustable members of the mattress support to provide a transverse opening through the bed, and elevating the receptacle into said opening for use.

4. In a device of the class described, a 80 frame of open structure, a mattress support carried on the frame, a mattress carried on the mattress support, means for providing a closable opening through the mattress and mattress support, a receptacle secured to the 85 frame and disposed under said closable opening, an adjustable cover for covering the receptacle, and means secured to the frame and operable by the occupant of the bed for synchronously providing an open- 90 ing through the mattress and mattress support, elevating said receptacle into said opening for use, and withdrawing the cover from the receptacle, said means including means to restore said adjustable members to 95 their original positions.

5. In a device of the class described, a frame of open structure, a mattress support carried on the frame, a mattress carried on the mattress support, means for providing 100 a closable opening through the mattress and mattress support, a movable support secured to the frame and disposed under said closable opening, a receptacle carried on said movable support, a covering provided over 105 the receptacle, means operable by the occupant of the bed for elevating and lowering said receptacle and receptacle support, including means operable by said receptacle adjusting means for synchronously withdrawing said covering from its normal position over the receptacle when the receptacle is elevated toward said closable opening and restoring said covering to its normal position when the receptacle is withdrawn from 110 said opening.

In testimony whereof I hereunto affix my signature in presence of two witnesses.

JOSEPH E. FAZAKERLEY.
